DISHWASHING MACHINE

Filed March 18, 1929

FIG. 1.

FIG. 3.

UNITED STATES PATENT OFFICE

JOHN E. LEDERMAN, OF MILWAUKEE, WISCONSIN, ASSIGNOR TO HYDRO ELECTRIC MANUFACTURING COMPANY, OF MILWAUKEE, WISCONSIN, A CORPORATION OF WISCONSIN

DISHWASHING MACHINE

Application filed March 18, 1929. Serial No. 347,933.

The invention relates to dishwashing machines.

Heretofore in dishwashing machines in which the washing liquid is sprayed from a rotating nozzle, either directly on the dishes or indirectly through deflection from the casing, it has been customary to mount the spray nozzle on a supply conduit provided with one or more plain holes that conduct the washing liquid to the arm or arms of the sprayer. It has been found in such constructions that the resistance to the passage of water to the arms through these holes is so great that considerable water escapes through the joint between the spray arm and its pivot, with a resulting loss in efficiency. This difficulty has been overcome in the present invention by providing large passages between the conduit and the arms and forming the top of such passages as a deflector, whereby the washing liquid is turned from an axial to a radial flow through the arms, with a minimum loss, and considerable saving in water necessary to wash the dishes is effected over prior constructions.

The invention further consists in the several features hereinafter set forth and more particularly defined by claims at the conclusion hereof.

30. In the drawings Fig. 1 is a vertical sectional view through a dishwashing machine embodying the invention;

Fig. 2 is a detail vertical sectional view through a spray arm and its mounting embodying the invention;

Fig. 3 is a plan view of a device embodying the invention, parts being broken away and parts being shown in section.

The particular dishwashing machine in connection with which the present invention is illustrated has been shown and described in my prior application, Serial No. 291,197, filed July 9, 1928, and for the purpose of the present invention it is pointed out that the machine includes a casing having side walls 4, a rear wall 5, a pivoted cover 6 forming a front wall, a dish basket 7 removably mounted on brackets 8 secured to the side wall, a bottom 9 provided with a drain opening 10 and a motor-driven pump 11 mounted below

the bottom in a compartment 12 on a suitable support 13, the washing liquid either being introduced directly into the machine or through a pipe 14 communicating with the pump.

A pivot fitting 15 has threaded connection 16 engaging with the outlet of the pump and a bore or passage 17 whose outlet is formed by large side openings 18 and a top 19 having inclined sides 20, said top being connected to the main body of the fitting by relatively narrow strips 21. The fitting also has a cylindrical portion 22 terminating at an angular shoulder 23 and a flat surface 24 from which a threaded exterior 25 projects.

The spray member includes a pivot fitting 26 having pipe arms 27 in threaded engagement therewith and provided with discharge openings 28 and 29, one or both of which may be inclined so as to produce rotation of the arm under the action of the washing liquid, as is common in sprinklers.

The fitting 26 has a bore 30 loosely fitting the cylindrical portion 22 and when at rest the upper end 31 of the fitting, which is of reduced diameter compared to the bore 30, may engage the surface 24. This end is threaded to receive a cap 32 and has a centrally disposed bore 33, through which the threaded extension loosely projects, with a conically formed seat 34 at its upper end.

A nut 35 of bronze or other suitable bearing material is threaded on the extension 25 and has a conically formed bearing portion 36 with which the seat 34 engages and it is, in accordance with well known sprinkler practice, the only part in end-thrust engagement with the arm while the pump is running, since the pressure of the liquid acting upwardly against the upper end of the fitting 26 and the cap lifts the arm from the surface 24 and serves to hold the spray arm against the bearing 36. The cap 32 extends over the extension 25 and the nut and closes off the upper end of the fitting 26.

With this construction the washing liquid from the pump is delivered through the bore 17, openings 18 to the arms 27, and thence through openings 28 and 29 into the casing where it strikes the dishes placed in the basket 7 either directly or indirectly through

deflection from the casing. It will be noted that the lower sides 37 of the openings 18 incline outwardly and downwardly from the ribs or strips 21.

5 As the washing liquid passes from the bore 17 through the openings 18 its flow is changed with a minimum of disturbance as the large openings and the inclined surfaces or sides 20 assist in changing its flow from an axial 10 to a radial direction and tests show that because of these features far more water is available at the spray tips than in prior constructions where radially disposed slots or holes were used, it being noted that the whole 15 upper end of the bore 17 opens into the pivot fitting 26 except for the narrow strips 21. The result is a saving in washing liquid and in consequence a saving of power to operate the machine and a more effective distribution of the liquid.

20 I desire it to be understood that this invention is not limited to any particular form or arrangement of parts except insofar as such limitations are included in the claims.

25 25 What I claim as my invention is:

1. In a dishwashing machine, the combination of a spraying device including a rotatable spray arm, a pivot fitting forming an inlet conduit for said arm provided with a 30 top deflector portion having sides inclining from the center outwardly and upwardly and relatively narrow parts connecting said portion with the main body of said fitting whereby the washing liquid is changed in its flow 35 from an axial to a radial direction without turbulence and resulting energy losses, a bearing for said arm mounted on said pivot fitting above said deflector portion, and a cap on said arm covering said bearing.

40 2. In a dishwashing machine, the combination of a spraying device including a rotatable spray arm, a pivot fitting having an inlet conduit portion provided with a top deflector and large side openings at its upper 45 end and a threaded extension, a conically curved bearing member mounted on said threaded extension, said spray arm having a tubular portion having a seat engaging said bearing member, and a cap fitting over said 50 tubular portion, said bearing member and said extension, said bearing member taking the full end thrust of the arm when the device is in operation.

In testimony whereof, I affix my signature.

55 JOHN E. LEDERMAN.
